UNITED STATES PATENT OFFICE.

BRUCE E. CLARKE, OF KANSAS CITY, MISSOURI.

FIREARM CARTRIDGE FOR SCENIC EFFECTS.

Application filed February 26, 1925. Serial No. 11,625.

To all whom it may concern:

Be it known that I, BRUCE E. CLARKE, a citizen of the United States, residing at Kansas City, in the county of Jackson and State of Missouri, have invented certain new and useful Improvements in Firearm Cartridges for Scenic Effects, of which the following is a specification.

This invention relates to a cartridge to be fired in a standard firearm, or an arm especially constructed to receive it, with the effect of closely simulating at least in visual effects, and preferably in audible effects as well, the conditions attendant upon the operation of the firearm under normal conditions.

The invention has for its object to provide a cartridge which can be produced, handled, and consumed without disagreeable consequences, and without danger incident to firing even though a person may be in the direct line of fire and at close range.

The invention proceeds upon the principle of suitably encasing within the cartridge a medium which, when expelled, will simulate the appearance of smoke from a firearm, together with a medium normally confined but releasable at will for expelling the smoke-simulating medium, and means whereby the expelling medium may be released to action by the act of functioning the firearm in which the cartridge is introduced; the smoke-simulating medium being preferably in the form of an impalpable powder confined in a powder chamber with a releasable closure resisting its escape from the cartridge; the under pressure, non-inflammable or explosive, and preferably inert; and the releasing and preferably inert; and the releasing means being preferably in the form of a piston or equivalent member standing in control of the releasable closure, and in turn subject to action of gases resulting from detonation of a primer or cap. The expelling medium may stand in communication with the smoke-simulating medium, the releasable closure which confines the latter being relied on also to resist escape of the former. In the preferred embodiment, the expelling medium is confined in the tubular body of the cartridge, while the smoke-simulating medium and the actuator, with its primer, are located in separate chambers associated with the expelling medium cylinder at the respective ends thereof.

In order that the invention may be fully understood, the preferred embodiment there-

of will now be described in detail, by way of illustration, reference being had to the accompanying drawing, in which—

Figure 1 is an axial section of a cartridge involving the several features of the present invention.

Figure 2 is a similar view on a larger scale of the rear end of the same.

Figure 3 is a similar view on an enlarged scale of the front end of the cartridge; and

Figure 4 shows an axial section of a modified construction of the rear end.

1 represents the tubular body of a cartridge shell which is preferably constructed with a substantial base 2, having a flange 3 and with a frusto conical end 4, the cartridge being thereby adapted for convenient introduction and proper positioning in the chamber of a firearm. The forward end 4 is designed with a thickened portion 5, into which is screwed the supporting end 6, and a chamber 7 designed to carrying a smoke-simulating medium, for instance, an impalpable powder that will readily float in suspension in atmospheric air. While any powder answering to these conditions may be employed for this purpose so long as its color will be appropriate for the visual effect desired, I have found by experiment that there is one substance which is peculiarly adapted for this purpose, namely, Lycopodium, which, because of its light weight, will closely simulate products of combustion and gradually float away until the floating mass becomes dissipated or attenuated to the degree of dissolving from view. The chamber 7 is preferably threaded, through the medium of its head 6, into the thickened portion of the head 4 so that it can be readily removed and replaced in discharging the cartridge; and it has a funnel shaped discharge end 8 normally closed by a destructible filling piece 9 adapted to be punctured by a needle rod 10; also an inverted funnel-shaped bottom 11 through which the rod 10 passes and which by its shape reduces to a minimum the powder escaping rearwardly through the rod opening.

Cylinder 1, which constitutes by far the greater volume of the internal space of the cartridge, is designed to contain a gas under pressure sufficient to forcibly expel the powder in the chamber 7 and atomize it so that it will remain in suspension and float off on the atmosphere. The gas employed for this purpose may be atmospheric air,

carbon dioxide, or even nitrogen, each of which has the inherent quality of being readily confined under pressure, of being inert, and therefore harmless and unobjectionable to animal life when released; and the expelling medium thus developed is preferably left in normal communication with the interior of the chamber 7, through the medium of the space 12 existing between the rod 10 and the conical bottom 11. In other words, the destructible filling piece 9 serves as the means for confining the expelling medium under pressure, as well as for resisting escape of the smoke-simulating medium.

15 In the thickened base 2 of the cartridge is threaded a cylinder 13 for an actuating piston 14 on the rear end of the rod 10, and this cylinder 13 is equipped with a convenient form of gas generator 15 for acting 20 upon the piston 14, for instance, the primer or detonator ordinarily used in a firearm cartridge, and which generally contains fulminate of mercury or other composition detonated by the firing pin of the arm. I have 25 found by experiment that the gas generated by detonation of such a primer when caused to act upon a piston such as 14, is quite sufficient to develop a forcible thrust in the rod 10 and cause the latter to puncture the filling 30 piece 9 and release the gaseous expelling medium from the cylinder 1 together with the smoke simulating powder of the chamber 7 which is borne out in suspension upon the gas. In order to avoid possible ill effects 35 of projection of the filling piece 9 along with the blast of powder-expelling gas, said piece is anchored in the forward end of the chamber head 6 by dovetailing it therein, and in order that the needle end of the bar 40 10 may not unduly obstruct the perforation which it makes, a return spring 16 of very substantial capacity is inserted between the piston 14 and the forward end of the cylinder 13, so that immediately the piston completes 45 its stroke and causes the rod to penetrate the filling piece 9, the rod will be withdrawn from the discharge opening. By way of insuring against undue delay in the withdrawal of the needle from the destructible closure or filling piece 9, cylinder 13 is 50 suitably vented, for instance, as shown at 17, so that remnant gas from the detonator will be quickly reduced in pressure upon attainment, by the piston 14, of its forward limit of movement, and thus leave the return spring 16 without undue resistance to its action of withdrawing the needle bar from the punctured closure.

55 If desired, the cylinder may be in the form shown at 13^a in Figure 4, according to 60 which it is constructed with a seat 13^b against which the piston 14^a may rest in its outward movement under the spring 16 and thus be adapted to serve as a check valve in 65 the charging of the container 1 with expel-

ling medium under pressure, as, for instance, by introducing a gas connection at the primer opening 15^a and after getting the desired pressure in the container 1, relying on the piston 14^a to serve as a valve 70 until the primer 15 can be introduced. Otherwise, charging with expelling medium under pressure will have to be carried on in an apparatus equipped with means for introducing the primer before removing the cartridge from the pressure supplying medium. 75

I have discovered by experiment that lyco-podium is a particularly desirable substance to use in the chamber 7 as a smoke-simulating medium, because of its appropriate color, its ready suspension in atmosphere, its non-packing quality, and its total lack of disagreeable effect upon the eyes or respiratory organs. If nitrogen or carbon dioxide be used as the expelling medium in chamber 1, other forms of smoke-simulating medium may be used in the chamber 7, even though the substance be such as to be practically explosive when suspended in fine subdivided form, since in this circumstance there will be nothing to convey ignition from the primer 15 to the smoke-simulating medium. 80 85 90 95

I claim:

1. In a cartridge for spectacular effects, a chamber for smoke-simulating medium, a reservoir for gaseous expelling medium, and means for releasing said smoke-simulating medium and expelling medium at will. 100

2. In a cartridge for spectacular effects, a chamber for a gaseous expelling medium, a chamber adapted to contain a smoke simulating medium, the last-named chamber having a port for communicating with the chamber first named, and having a port through which its contents can escape to atmosphere when borne upon the expelling medium, and means for opening the second named chamber to atmosphere at will. 105 110 115

3. A cartridge for spectacular effects, comprising a container for smoke-simulating medium, a container for a gaseous expelling medium, a closure for the chamber first named, releasable to open said chamber to atmosphere, an actuator adapted to open said closure, and means for driving said actuator comprising a piston and a gas generator in position to deliver gas under pressure to said piston. 120

4. In a cartridge for spectacular effects, a cylindrical body, a chamber for smoke-simulating medium mounted in one end of said body, having a port at its forward end through which it is adapted to communicate with atmosphere, and a port at its rear end through which it communicates with the interior of the body, a closure for said port, a rod adapted to open said closure, and means for controlling said rod at will. 125 130

5. In a cartridge for spectacular effects, a container for gaseous expelling medium, a chamber for smoke-simulating medium having a discharge port and a port through 45
5 which it communicates with said container, and a thrust rod entering said chamber from said container for opening the discharge port of the chamber; said chamber having an inturned conical body through which said 10 thrust rod passes.
6. In a cartridge for spectacular effects, a container for gaseous expelling medium, a chamber for smoke simulating medium having a port through which it discharges and a 15 port through which it communicates with said container, a closure for the discharge port of said chamber, and a thrust rod for opening said closure.
7. In a cartridge for spectacular effects, a 20 container for gas-expelling medium, a chamber for smoke-simulating medium having a discharge port and a port through which it communicates with said container, a filling piece anchored over said discharge port and 25 adapted to close the same, and a thrust rod adapted to puncture said filling piece without dislodging it.
8. In a cartridge for spectacular effects, a 30 body portion adapted to contain a gaseous expelling medium, and a chamber for smoke-simulating medium replaceably mounted in the forward end of said body portion and having a port through which it discharges and a port through which it communicates 35 with the interior of said body portion.
9. In a cartridge for spectacular effects, a 40 body portion adapted to contain a gaseous expelling medium, said body portion having a threaded forward end, and a chamber for smoke-simulating medium inserted through the forward end of the body portion, having threaded connection therewith.
10. In a cartridge of substantially the 45 character described, a body portion, a thrust rod, a piston on said thrust rod, a cylinder 50 surrounding said piston, and a gas generator in position to deliver gas under pressure to said piston.
11. In a cartridge of substantially the 55 character described, a body portion, a thrust rod, a piston on said thrust rod, a cylinder surrounding said piston, and a gas generator in position to deliver gas under pressure to said piston; said piston having a spring acting upon it in the direction opposite to that in which it is projected by the gas pressure.
12. In a cartridge of substantially the 60 character described, a body portion, a thrust rod, a piston on said thrust rod, a cylinder 65 surrounding said piston, and a gas generator in position to deliver gas under pressure to said piston; said cylinder being vented in rear of the forward limit of movement of the piston.
13. In a cartridge of substantially the 70 character described, a body portion adapted to contain a gaseous expelling medium, a cylinder inserted in the rear end of said body portion, a thrust rod entering said cylinder, a piston for actuating said thrust rod, and a gas generator adapted to be operated upon at will to deliver gas under pressure 75 to said piston; said cylinder having ports in rear of the forward limit of movement of the piston and delivering into the body of the cartridge and to said expelling medium the gas under pressure remaining at the end of the stroke of the piston.
14. In a cartridge for spectacular effects, 80 a chamber containing lycopodium, means for venting said chamber at will, and a reservoir of gaseous expelling medium adapted to deliver its contents in expelling relation to the contents of said chamber.
- Signed at Chicago, Illinois, this 30th day 85 of December, 1924.

BRUCE E. CLARKE.
